UNITED STATES PATENT OFFICE.

ARTHUR H. PETERS, OF FORT WAYNE, INDIANA.

GEARING FOR WASHING-MACHINES.

1,391,272.

Specification of Letters Patent. Patented Sept. 20, 1921.

Application filed August 2, 1916. Serial No. 112,641.

To all whom it may concern:

Be it known that I, ARTHUR H. PETERS, a citizen of the United States, residing at Fort Wayne, in the county of Allen and State of Indiana, have invented certain new and useful Improvements in Gearings for Washing-Machines, of which the following is the specification.

This invention relates to gearing for washing machines, and particularly for a novel construction and arrangement whereby a more efficient washing action takes place.

It is an object of the invention to provide gearing for washing machines of compact and simple construction, whereby an attached wringer may be driven efficiently and with the minimum loss of power, and whereby the lid of the washing machine may be raised and lowered during the washing operation without sacrificing energy stored up in the fly wheel.

It is another object to provide a vacuum washer and associated parts so constructed and arranged that the vacuum washer positively travels about inside the tub and covers substantially the entire bottom thereof in its direct operation so as to absolutely insure the treatment of all of the material in the tub.

Other objects and advantages of the invention will appear as the description to follow proceeds.

In the drawings:—

Figure 1 is an elevation of a washing machine constructed according to my invention.

Fig. 2 is a top plan view thereof.

Fig. 3 is a cross sectional elevation.

Fig. 4 is an enlarged detail cross sectional view showing a portion of the operating mechanism.

Fig. 5 is a bottom plan view of the dolly.

Fig. 6 is a fragmentary detail cross sectional view showing the valve construction.

1 represents a washing machine tub mounted upon legs 2, equipped with a platform 3, upon which I may mount an electric motor 4. A portion 5 of the tub is prolonged to provide a support for the bearing 6. In line with the bearing 6, is a bearing 7 in a bracket 8 bolted to the top of the tub, as indicated, and having bearings 9, to accommodate a vertical wringer shaft, the construction being such that a wringer may be

mounted in its usual position 10 and driven by a vertical shaft having bearings 9. The lid of the tub 11 is of usual construction and has its hinged line parallel to the line of the bearings 6 and 7. Mounted in the bearings 6 and 7 is a shaft 12, having at one end the gearing 13 for driving the wringer and at the other end the gearing 14 carrying the stub 15, which is pivotally connected at one end with the pitman 17 and at its other end connected with the flange 18, upon the casting 19, pivoted upon the stub 20, projecting from the casting 20', firmly bolted to the side of the tub. The casting 19 has sockets 21 for the reception of the handle 22.

The casting 20' has projecting therefrom a stub 23, upon which is mounted a fly-wheel 24, the rim of which is adapted to receive a belt 25 so as to be capable of being driven by the motor 4. Integral with the fly-wheel, is a small pinion 26 in mesh with the gear 14, so that when not motor driven the fly-wheel 24 serves as an energy storing device. The gear 14 drives the outer idler of a pair of idlers 27 mounted on a stub projecting from the plate 28 firmly bolted to the extended portion 5 of the tub. Mounted upon the hinged cover, is a bearing plate 30 carrying a pair of brackets 31 forming bearings for the horizontal shaft 32, carrying at one end the gear 33 meshing with the inner idler 27 and carrying at its opposite end the crank 29. The bearing plate 30 has adjacent the center of the tub a vertical bracket 34, which provides a bearing at 35 for the reciprocatory and rotary shaft 36, which has another bearing at 35' in the bearing plate 30 and passes through the cover, as clearly shown. The crank 29 has at its end a cylindrical aperture 37, in which is revolvably and slidably mounted the plug 38, connected to the pin 39, firmly mounted in the arm 40, which is revolvably mounted as by means of a bushing 41 on the shaft 36 and confined thereon between the two rigidly mounted collars 42 and 43. Above the collar 42, is loosely seated the compression spring 44. At the bottom of the shaft 36, is fastened the eccentric boss 45 upon the vacuum washer 46, which comprises a dome having at its bottom the perforated plate 47 secured therein by screws, such as 48, taking into bosses 49 in

the interior of the bell or dome 46. The perforated plate has washer wings 50 thereon and is provided with a plurality of apertures. The bell 46 is provided at its top 5 with a plurality of apertures 51 covered by a plate 52, provided with a rubber or other suitable washer 53 and mounted upon the end of the screw 54, which projects through the dome 46, a space being left 10 between the head of the screw 54 and the inner surface of the dome 46 to permit the closure formed by the plate 52 to be raised from its seat.

Mounted in the bearing plate 30 is the 15 stub shaft 60, provided with a handle 61 at its outer end and at its inner end with a latch 62 engaging with a notch in the casting 20' bolted to the side of the tub. A spring operated plunger 63 working in a 20 recess in the bearing plate 30 tends to force the latch 62 outwardly and keep it in engagement with the notch. The purpose of these parts is to keep the hinged cover securely locked down even though the pressure imposed upon the clothes by the washer 25 head 46 be considerable. When it is desired to raise the cover, it is only necessary to pull up the handle 61, whereupon the hinged cover is released.

30 In operation, the washer may be driven either from the handle 22 or by the motor 4. In the first event, the fly wheel 24 serves as an energy storing device; in the second, it serves as a belt pulley to communicate 35 power to the washer. The gear 14 communicates power in either event to the idlers 27, the inner of which drives the gear 33, thus operating shaft 32 and crank 29. Since the arm 40 is confined against longitudinal 40 movement on the shaft 36 by the collars 42, the rotation of the crank 29 will cause the vertical reciprocation of the shaft 36. While the crank is at its highest position, however, the spring 44 will be compressed between the 45 collar 42 and the bearing 35 at the top of the bracket 34, the parts being so positioned as to cause this, which means that increased pressure over and above that of the weight of the washer will be caused between the 50 arm 40 and the collar 42. Inasmuch as the washer head 46 is at this time lifted over and clear of the clothes in the tub, and little, if any, obstruction is presented to the revolution of the shaft 36, this increased pressure 55 between the arm 40 and the collar 42 will result in the shaft 36 being rotated during the upper portion of the cycle of the crank 29. As the crank 29 moves through the lower portion of its cycle, the shaft 36 is dropped 60 again, and the spring 44 falls with it, as shown in Fig. 4. In addition to this, the washer head 46 is in contact with clothes being washed and therefore rotation is no longer possible. The effect of the action 65 above described is that the washer head 46 is

raised, partially rotated, and dropped again, always turning to a new position at the top of its stroke and going straight down thereafter upon the clothes. This pounder head walks or steps about substantially the entire 70 bottom of the tub and thus equally affects all of the material therein.

The operation of the washer head itself is a vacuum one. As the head is lowered upon the clothes, air and suds are discharged 75 through the apertures 51 under the valve plate 52, which is lifted by the out-rushing air, this lift being permitted by the space between the head of the screw 54 and the top of the inner portion of the dome 46. When 80 the pounder head is raised, however, the plate 52 closes the apertures 51 and causes a partial vacuum inside the dome 46, which positively draws suds, water and air through the clothes as the vacuum washer is raised, 85 thus increasing the cleansing action of the machine by vacuum operation as well as by mechanical shifting and striking of the clothes.

Having now described my invention, I 90 claim:—

1. In gearing for washing machines, a support, a driving shaft located on the support, a driven shaft mounted upon the side of the support, a hinged member upon the support, a shaft mounted in said hinged member, separable gear connections between said shaft on said hinged member and said driven shaft, a crank on said shaft mounted on said hinged member, a vertical 95 rotary and reciprocatory shaft mounted in said hinged member and a connection between said vertical shaft and said crank so designed that the former may be intermittently rotated and reciprocated by the 100 latter.

2. In gearing for washing machines, a support, a driving shaft on said support, a hinged member on the support, a shaft on 110 said hinged member, a crank on said shaft, a vertical rotary reciprocatory shaft mounted in said hinged member; means connecting said vertical shaft with said crank to cause said vertical shaft to be reciprocated, and during such reciprocation intermittently rotated in one direction only by said crank, and driving connections between said driving shaft and said shaft on said hinged member, said means for intermittently rotating said vertical shaft comprising pressure friction means operable while the crank arm is passing through its upper arc of movement.

3. In apparatus of the class described, a support, a lever pivotally connected to the 125 support, a pitman pivotally connected at one end with the lever, a gear wheel mounted upon the support and driven by said pitman, a fly-wheel driven by said gear wheel, an idler driven by said gear wheel, a hinged 130

member mounted upon the support, a horizontal shaft mounted on the hinged member, and a gear on said horizontal shaft driven by said idler, substantially as described.

4. In apparatus of the class described, a support, a lever pivotally mounted thereon, a shaft mounted on the support, a gear on said shaft, a connection between said gear and said lever whereby the former may be driven from the latter, a hinged member on the support, a horizontal shaft mounted in the hinged member, gear connections between said gear and said horizontal shaft mounted on the hinged member whereby the latter may be driven from the former, said gear connections being separable so as to be interrupted when the hinged member is raised.

5. In apparatus of the class described, a support, a shaft mounted therein, a vertical shaft at one end of said first-mentioned shaft, a gear at the other end of said shaft, a lever in the support, driving connections between said lever and said gear, a hinged member on the support, a vertical reciprocatory and rotary shaft mounted in said hinged member, a horizontal shaft for driving said vertical reciprocatory shaft, separable gear connections between said gear and said horizontal shaft, and a fly-wheel driven by said gear for storing up momentum, substantially as described.

6. In apparatus of the class described, a support, a shaft mounted thereon, a driving gear on said shaft, a hinged member on the said support, a horizontal shaft on said hinged member, and driving connections, including an idler, between said gear and said horizontal shaft, substantially as described.

7. In gearing for washing machines, a support, a driving shaft on said support, a hinged member on the support, a shaft on said hinged member, a crank on said shaft, a vertical rotary reciprocatory shaft mounted in said hinged member, a laterally extending arm rotatably mounted on said vertical shaft, means connecting said laterally extending arm with said crank to cause said vertical shaft to be reciprocated, and during such reciprocation to be intermittently rotated in one direction only, said means comprising spring pressed means frictionally engaging said arm for rotating said shaft adjacent its limit of longitudinal movement, and driving connections between said driving shaft and said shaft on said hinged member.

8. In apparatus of the class described, a support, a hinged member mounted thereon, a horizontal shaft mounted on said hinged member, a vertical reciprocatory shaft mounted in said hinged member, a crank upon said horizontal shaft, an arm upon said vertical reciprocatory shaft having piv-

otal connection with the end of said crank, collars on said vertical reciprocatory shaft confining said arm, and means to augment the pressure between one of said collars and said arm during a portion of the revolution 70 of said crank.

9. In apparatus of the class described, a support, a hinged member mounted thereon, a vertical reciprocatory shaft mounted in said hinged member, a crank and a crank 75 shaft mounted on said hinged member, an arm upon said vertical reciprocatory shaft, pivotally connected to said crank and revolvably mounted on said vertical reciprocatory shaft, a collar above said arm upon said vertical shaft and non-rotatably mounted thereon, a spring loosely mounted on said shaft above said collar, and a bracket forming a bearing for said vertical shaft above said spring, whereby as said crank shaft revolves 80 said vertical reciprocatory shaft will be raised until said spring is compressed between said bracket and said collar and the pressure thereby augmented between said arm and said collar, causing a partial rotation of said vertical shaft during a portion of the revolution of said crank.

10. In apparatus of the class described, a shaft having a crank thereon, a shaft arranged at right angles thereto, an arm revolvably mounted upon the second mentioned shaft and pivotally connected to said crank, a collar rigidly mounted adjacent said arm on said second mentioned shaft, a stop mounted adjacent said shaft, and a spring 100 interposed between said collar and stop, all so constructed and arranged that the spring will be compressed between said collar and said stop as said collar is moved during the revolution of said crank, substantially as 105 described.

11. In apparatus of the class described, a support, a hinged member mounted thereon, a horizontal shaft on said member, a vertical shaft mounted in said member, a crank 110 on said horizontal shaft, a horizontal arm revolvably mounted on said vertical shaft and having driving connection with said crank, and means on said vertical shaft to cause the same to be intermittently rotated 115 and reciprocated as said crank raises and lowers said horizontal arm.

12. In apparatus of the class described, a support, a vertical reciprocatory shaft rotatably mounted on said support, means on said support for reciprocating said shaft and comprising two slidably contacting surfaces, and means for increasing the pressure between said surfaces at a given portion of the reciprocatory travel of the shaft sufficiently to cause said surfaces to move together to cause said shaft to periodically rotate.

13. In apparatus of the class described, a support, a vertical reciprocatory shaft ro- 130

tatably mounted on said support, means on said support for reciprocating said shaft and comprising two slidably contacting surfaces, one of said surfaces being so associated with the vertical shaft that its rotation will cause rotation of the vertical shaft, and means for increasing the pressure between said surfaces at a given portion of the reciprocatory travel of the shaft sufficiently

to cause said surfaces to move together to 10 cause said shaft to periodically rotate.

In witness whereof, I hereunto subscribe my name to this specification in the presence of two witnesses.

ARTHUR H. PETERS.
